DESIGN FOR A BLOUSE

Murray Presslaff, New York, N. Y.

Application January 4, 1938, Serial No. 74,068

Term of patent 3½ years

To all whom it may concern:

Be it known that I, Murray Presslaff, a citizen of the United States of America, residing in the city of New York, county of New York, and State of New York, have invented a new, original, and ornamental Design for a Blouse, of which the following is a specification, reference being had to the accompanying drawing, forming part thereof.

Fig. 1 is a front view of a blouse showing my new design.

Fig. 2 is a rear view thereof.

The characteristic feature of my design resides in the specific arrangement of the elastic shirred fabric on the front bottom portion of the blouse as shown.

I claim:

The ornamental design for a blouse, substantially as shown and described.

MURRAY PRESSLAFF.
